WILLIAM A. VOCK, OF LONG BEACH, AND AMOS C. TOWNE, OF LOMITA, CALIFORNIA

WELL TOOL

Application filed June 25, 1928. Serial No. 288,170.

This invention has to do with a well tool and relates particularly to that type of tool known generally as a spear. It is an object of the invention to provide a simple, practical, and improved tool of this general type.

An object of our present invention is to provide a spear operable to tightly grip a casing, or the like, and capable of being released from the casing, if desired.

10 Another object of the invention is to provide an improved formation and mounting for slips in a tool of the character described whereby they operate effectively and without binding.

15 Another object of this invention is to provide a simple, effective, and strong slip mechanism operable to grip a casing for longitudinal movement and to be operated to rotate a casing.

20 Another object of our invention is to provide a simple, practical, and dependable means for controlling the slips of a spear so that they can be released for operation or released from operating position at the will 25 of the operator.

It is another object of this invention to provide a spear such as we have referred to embodying a few simple, effective, and durable parts.

30 The various objects and features of our invention will be best and more fully understood from the following detailed description of a typical form and application of the invention, throughout which description reference is had to the accompanying drawings, in which:

Fig. 1 is an exterior side elevation of the spear provided by our invention showing it in a well casing and released or unactuated in which position it can be moved in either direction through the casing. Fig. 2 is a view similar to Fig. 1 showing certain parts of the device in section and showing the device actuated or in operating position gripping the casing. Fig. 3 is a longitudinal detailed sectional view of the device showing the parts in the position illustrated in Fig. 1. Fig. 4 is a detailed transverse sectional view 50 taken as indicated by line 4-4 on Fig. 1, and

Fig. 5 is a detailed transverse section view taken as indicated by line 5-5 on Fig. 2.

The tool provided by this invention includes, generally, a body 10, casing engaging members or slips 11, a tapered or wedge part 55 12 on the body for expanding the slips, an enlargement or head 13 on the body at a point spaced from the wedge 12, a sleeve 14 slidably mounted on the body between the wedge 12 and head 13, control means 15 in connection with the sleeve and head, and various other parts the details and functions of which will be hereinafter described.

The body 10 is an elongate centrally located member operating as a carrier or support for the various other principal parts of the device. The body 10 may be round in cross sectional configuration and may be provided with a central longitudinal circulation opening 16 as shown in the drawings.

60 The wedge 12 is preferably in the form of an enlargement at or on the lower end of the body 10. In the particular tool illustrated the wedge is round in cross section and is made downwardly divergent, as clearly 65 shown throughout the drawings. In the construction illustrated, the wedge is integral with the body and is provided at its lower or large end with an upwardly projecting part or stop 17 operable to permit 70 displacement of the slip from the wedge. In practice a central screw-threaded socket 18, or the like, may be provided at the lower end of the structure just described to receive any 75 part or device that an operator may desire 80 to attach to the tool.

85 The slips 11 may be of the type ordinarily provided in well tools of this character. For instance, the outer faces of the slips may be 90 provided with gripping parts or teeth 19 to engage the casing 20 in which the tool is operated. The slips may be of various sizes and there may be various numbers of slips. In the drawings we have shown three slips 95 of equal size symmetrically arranged on the wedge 12. In accordance with the present invention the inner side or face of each slip has an upper bearing portion 21 slidably fitting the body 10 and a lower bearing portion 22 formed at an angle to cooperate with 100

the face of the wedge 12. Further, in accordance with the invention we provide means locking the wedge and slips against relative rotary motion. This means preferably includes ribs or projections 23 on the exterior of the wedge slidably fitting longitudinally-disposed slots 24 formed in the slips from their lower ends. The base or inner portions of the projections 23 are dove tailed into suitable recesses 25 provided in the wedge 12, as clearly illustrated in Fig. 5 of the drawings. In practice a free sliding fit is provided between the projections 23 and the slips 11, which fit is maintained during the various operations of the tool.

The head 13 is in the nature of an enlargement on the body 10 and is located at the upper end of the body. In the case illustrated the head 13 is detachable from the body being screw threaded on the upper end of the body. The head has an internal shoulder 30 forming an abutment for the upper end of the body as clearly shown in Fig. 3. The head may project above the body and have a screw-threaded part, for instance a socket 31, whereby the tool can be connected with an operating member such as a string of drill pipe 32, or the like.

The sleeve 14 is slidably and rotatably carried on the body 10 intermediate the wedge 12 and head 13. The sleeve is connected with or carries the slips 11 for the purpose of actuating them with reference to the wedge. In the construction illustrated each slip is provided at its upper end with an extension 33 having enlargements 34 at its outer end. An annular flange 35 projects from the lower end of the sleeve over the extensions 33 to overhang the enlargements 34, as clearly shown in Figs. 2 and 3 of the drawings. The parts just referred to are fitted or related so that the sleeve is free to rotate relative to the slips but is connected with the slips to move them longitudinally with reference to the body and wedge.

The sleeve 14 is provided with means to frictionally engage the casing 20 so that the sleeve resists movement in the casing. In practice this means may comprise a plurality of spring members carried by the sleeve to project outwardly from it and bear against the interior of the casing 20 as shown throughout the drawings. In the preferred construction the spring members 40 are mounted in recesses 41 provided at the exterior of the body, the recesses operating to brace the springs laterally.

The control means 15 operates between the sleeve 14 and the body 10 or the head 13, which may be considered a part of the body. The control means 15 provides a releasable connection between the sleeve and head whereby the head and sleeve are connected to move together in a longitudinal direction or can be released to move relative to each other in

a longitudinal direction. The means illustrated is such as to be actuated by relative rotation between the head and sleeve. The form of means illustrated in the drawings includes one or more arms 50 projecting upwardly from the sleeve to slidably operate in guideways 51 extending into the head, from its lower end and lateral projections or lugs 52 on the upper ends of the arms to cooperate with lateral openings or notches 53 at the upper ends of the guideways 51. In the construction illustrated there are two arms 50 and cooperating parts located diametrically opposite each other. Each guideway 51 is sufficiently wide to accommodate or slidably carry its cooperating arm 50 and lug 52, allowing free movement of the parts between positions such as are shown in Figs. 1 and 2. The lug fits the notch 53 at the upper end of the guide as shown in Fig. 1 so that the head 13 and sleeve 14 have to be moved relative to each other in a rotary direction and also somewhat longitudinally in order to disengage the lug from the notch. When the lug is in the notch, the lower end of the head 13 may engage the upper end of the sleeve 14.

In operation the tool is operated through the casing 20 with the parts positioned as shown in Figs. 1 and 3. With this positioning of parts, the sleeve 14 is set or held in the up position on the body in which position the slips are in an up position on the wedge and therefore unactuated or unexpanded. When it is desired to actuate the tool to grip the casing, the head is rotated through the operating member 32 so that the lugs 52 are disengaged from the notches 53 allowing the head and body, and therefore the wedge, to be lifted or moved upwardly with reference to the sleeve, causing the wedge to expand the slips into gripping engagement with the casing. It will be apparent that the slips engage the casing so that it can be lifted or moved longitudinally or can be rotated by rotating the member 32. It will be obvious that rotational strain from the member 32 is applied through the body 10, wedge and projections 23.

In the event that it is desired to release the tool from the casing, the head 13 can be lowered with reference to the sleeve 14 until the lugs 52 are opposite their notches 53 whereupon rotation of the head 13 in the proper direction will cause the lugs to be engaged in the notches as shown in Fig. 1. With the parts thus positioned, the slips are unactuated or free of the casing allowing the tool to be operated freely in either direction through the casing. It will be apparent that the tool can be operated or released as many times as desired without removing it from the casing.

Having described only a typical preferred form of our invention, we do not wish to limit ourselves to the specific details set forth, but wish to reserve to ourselves any changes

or variations that may appear to those skilled in the art or fall within the scope of the following claims.

Having described our invention, we claim:

5. 1. A well tool of the character described including a body, a wedge carried by the body, slips to be expanded by the wedge, and means operable to control operation of the slips including a releasable connection between the body and slips including a member carrying the slips and mounted on the body for rotation and longitudinal movement, and means controlled by relative rotation between the body and said member for releasably holding
- 10 15 said member against longitudinal movement with the slips unactuated, and including a projection on the member extending into a guideway on the body and a lug on the projection to cooperate with a recess in the guideway.
- 20 2. A well tool of the character described including a body, a wedge carried by the body, slips to be expanded by the wedge, and means operable to control operation of the slips including a releasable connection between the body and slips including a member carrying the slips and mounted on the body for rotation and longitudinal movement, and means controlled by relative rotation between
- 25 30 the body and said member for releasably holding said member against longitudinal movement with the slips unactuated, and including a projection on the member extending longitudinally of the body into a guideway on the body and a laterally projecting lug on the projection to cooperate with a recess in the guideway.
- 35 3. In a well tool of the character described a wedge, slips arranged for actuation by the wedge, and a longitudinal projection on the wedge extending into a longitudinally-disposed opening in one of the slips, the projection being attached to the wedge through a dove-tailed part fitting an opening in the wedge.
- 40 45 4. In a well tool of the character described, two members, one a body, the other a sleeve carried on the body for rotation and longitudinal movement, a wedge carried by the body, slips connected with the sleeve adapted to be expanded by the wedge, and an arm on one member having a lateral lug to cooperate with an opening in the other member for releasably holding the slips against operation
- 50 55 and being releasable upon relative rotation of the members, the opening having a part receiving the lug to prevent relative longitudinal movement between the members in either direction.
- 60 65 In witness that we claim the foregoing we have hereunto subscribed our names this 14th day of June, 1928.

WILLIAM A. VOCK.
